UNITED STATES PATENT OFFICE.

ELIAS ANDREASEN SCHMIDT, OF COPENHAGEN, DENMARK.

MACHINE FOR WASHING BOTTLES.

Application filed August 28, 1920. Serial No. 406,707.

To all whom it may concern:

Be it known that I, ELIAS ANDREASEN SCHMIDT, residing at No. 128 Vesterbrogade, Copenhagen, Denmark, have invented certain new and useful Improvements in and Relating to Machines for Washing Bottles, of which the following is a specification.

This invention relates to machines for washing bottles.

10 The object of the invention is to provide an improved machine whereby safe and perfect cleansing of bottles may be effected without the use of brushes or the like.

According to the invention the bottles after having been soaked and filled with warm water, are suddenly exposed to a blast of highly compressed air which ejects the water and impurities, whereupon the bottles are again filled with warm water and finally 20 emptied and rinsed with cold water.

The invention is illustrated in the accompanying drawings, according to one form of machine.

Figure 1 shows a vertical longitudinal section of the machine on the line I—I of Figure 1.

Figure 2 is a horizontal longitudinal section on the line II—II of Figure 4.

Figure 3 is a vertical section on the line III—III in Figure 1.

Fig. 4 is a horizontal section on the line 4—4 of Fig. 2.

Fig. 5 is an elevation of the machine at the bottle receiving end;

Fig. 6 is an elevation of the end of the machine from which the bottles are discharged; and,

Figs. 7 and 8 are top plan views of the right and left hand portions of the machine, 40 respectively.

Referring to the drawing 1 is a tank in which is fitted an endless conveying band consisting of two roller chains 2 and of a jointed bottle conveyer mounted between the 45 chains. The conveyer consists of narrow pieces 4 hinged together by bolts 3 and with funnel formed holes 5 for receiving the bottles.

The conveyer passes over a chain wheel 6 at one end of the tank 1 and over two chain wheels 7 and 8 mounted below each other at the other end of the tank, the upper edge of the chain wheel 7 being higher than the upper edge of the chain wheel 6 in such way

that the conveyer, which is moved in the 55 direction of the arrows, will be moved upward and inclined from the wheel 6 to the wheel 7.

A wheel 9 is provided for each chain, serving as a tension pulley, which can be adjusted by turning a hand wheel.

The conveyer is moved intermittently by a shaft 17 fitted on the tank and having two crank discs 10 of which each moves its crank arm 11 which is connected to one end of a 65 two armed lever 12, 13, the other end of which is fitted with a pawl 14 co-operating with a pawl disc 15 applied on the shaft 16 of the wheel 7.

The shaft 17 is rotated by means of a 70 toothed gearing 21 from the main shaft 19 driven by a spur wheel 18 which shaft by another toothed gearing 22 turns another shaft 20.

At one end of the machine (see the left 75 on Figure 1) a tray 23 is fitted in such way that each time the band is displaced, it will be turned from the position shown in Figure 1 into a sloping position, whereby one row of bottles placed with their necks foremost on the tray will glide into a corresponding row of receiving funnels 5 in a link piece 4. This movement of the tray 23 is due to a lever mechanism 24, 25, 26, 27, 28 moved by the shaft 20. 80

From the same shaft 20 a corresponding row of expulsion devices 33 is moved over a lever mechanism 29, 30, 31, 32, which is fitted on a frame 34. 85

Outside these expulsion devices is a tray 90 35, which likewise can be tilted by a lever mechanism 36, 37 which is moved from a cam disc 38 on the shaft.

From a compressor 39 with air tank 40, a pipe 41 conveys compressed air to a row 95 of air nozzles 42.

These are connected with the pipe 41 by air hose 43 and are fitted in sleeves 44, which are lifted by the lever mechanism 45, 46 from a cam 50 on the shaft 20. The conical lower ends 51 of the sleeves 44 in due time by their own weight pass down over the bottles, and the nozzles 42, when pressed down to the position shown in Fig. 2 will enter the neck of the bottle. Finally in the 105 pipe system 41, 43 a spring-loaded valve is fitted, which is not shown in the drawing but which from some moving member of

the machine, for instance, the lever 45, is opened at the moment when the nozzles 42 have entered the bottles.

The machine operates in the following 5 manner:—

By the pawl 14 the conveyor band is turned in such manner that every other link piece 4, each time the conveyor band stops, will be just in front of the insertion slot 46^a 10 in the left end of the machine, and there being an odd number of link pieces 4 each link piece 4 will only at every second turning of the band be in front of the said slot 46^a.

At the moment a link piece stops in front 15 of the slot 46^a, the tray 23 will be tilted, the outer end being swung upward by the lever connection, and in this way all the bottles lying on the tray will glide down into the corresponding funnels.

20 The bottles will now gradually pass through the steam filled upper part of the tank 1 above the surface of the water 47, whereupon they will be conveyed downward below the water, the bottoms of the bottles 25 gliding on a row of slides 48 which are applied at such a distance from each other that broken glass and heavy impurities will sink down between the slides to the bottom of the tank. When the bottles have passed 30 the wheels 8 (after having become filled with water while moving in a vertical position), the necks upward, back to the wheels 6, light impurities such as pieces of cork, wood and like will now get out of the bot- 35 tle and gather on the surface of the water 47.

When one row of bottles finally have 40 reached below the orifices 51 of the row of sleeves 44, they have first been heated by the steam of the tank thereafter filled with the warm water in the tank. Now the sleeves 44 will be moved downward in such manner that funnels 51 will enclose the necks of the bottles whereupon the nozzles 42, which like- 45 wise will move downward, will enter the necks of the bottles. At this moment the compressed air will be allowed to escape so that a blast of compressed air will pass from each of the nozzles 42 in the respective bot- 50 tles and force the water therefrom, and by causing a violent agitation of the water the bottles will be thoroughly cleaned.

The bottles will now pass through the slot 46^a without any delay, whereupon they will 55 be conveyed in reverse position towards the wheels 7, the water which again has filled the bottle thereby having discharged itself.

The bottles which are cleaned and emp- 60 tyed of the water will now, when passing the wheel 7 the second time, be in front of the expulsion devices 33, which by the lever mechanism 29, 30, 31, 32 will push out the bottles into a tray 35. As soon as the bot- 65 tles have been conveyed into the tray 35 the expulsion devices 33 will be conveyed back

to their places, partly by spring 53, partly by a two-armed lever 54, 55 moved by a cam 38.

From the tray 35 when turned upward in an inclined position by the lever mechanism 70 36, 37, the bottles will pass through guiding grooves 56 down to the funnels of the rinsing machine 49.

It is to be noted that instead of the arrangement described, a more simple 75 machine can be used on the same principle of the invention, the conveyor chain being replaced by a single conveyor wheel arranged for the simultaneous cleaning of one, two or more bottles.

Having now particularly described and ascertained the nature of my said invention and in what manner the same is to be performed, I declare that what I claim is:—

1. In a bottle washing machine, a closed 85 tank adapted to contain heated washing fluid and the vapor therefrom, bottle carrying means adapted to travel in said tank and operable to cause bottles to be filled with and submerged in the washing fluid, 90 means for feeding bottles to the carrying means whereby to effect heating of the bottles by vapor from the washing fluid preliminary to the submersion of said bottles, pneumatic means for forcibly ejecting the 95 washing fluid from the bottles during submersion in the washing fluid, and means for ejecting the bottles from the tank.

2. In a bottle washing machine a closed 100 tank adapted to contain heated washing fluid and the vapor therefrom, bottle carrying means having portions arranged above and below the level of the washing fluid, means for feeding bottles to the portion of the carrying means traveling above the level of the washing fluid whereby the bottles are heated by the vapors of the washing fluid preliminary to their submersion in said fluid, pneumatic means for forcibly ejecting the washing fluid from the bottles 105 at a point sufficiently distant from the point of removal of the bottles from the washing fluid to insure refilling of said bottles with the washing fluid subsequent to the operation of the pneumatic means, and means for 110 ejecting bottles from said carrier.

3. In a bottle washing machine, a closed 115 tank adapted to contain heated washing fluid and the vapor therefrom, bottle carrying means having portions arranged above and below the level of the washing fluid, bottle feeding means associated with the carrying means and located at one extremity of the tank, bottle ejecting means associated with the carrying means and located 120 at the opposite end of the tank, and means operating the bottle carrying means arranged to cause the incoming bottles to traverse the upper part of the tank and to be heated by the vapors therein and to cause 125

bottles to be subsequently submerged in the washing fluid, removed therefrom and emptied, said bottle carrying means operating to move the emptied bottles through the 5 vapor in the upper part of the tank preliminary to their ejection by the ejecting means.

In testimony whereof I affix my signature in presence of two witnesses.

ELIAS ANDERASEN SCHMIDT.
